UNITED STATES PATENT OFFICE.

GEORGE H. FERRIS, OF BROOKLYN, NEW YORK.

OIL-LAMP STOVE.

SPECIFICATION forming part of Letters Patent No. 268,655, dated December 5, 1882.

Application filed November 16, 1877.

To all whom it may concern:

Be it known that I, GEORGE H. FERRIS, of Brooklyn, in the county of Kings and State of New York, have invented certain new and useful Improvements in Oil-Lamp Stoves; and I do hereby declare the following to be a full, clear, and exact description of the same, reference being had to the accompanying drawings, forming a part of this specification, and in which—

Figure 1 represents a longitudinal vertical section of an oil-lamp stove constructed in accordance with my invention. Fig. 2 is a perspective view of the base of the stove and the parts composing the lamp. Fig. 3 is a plan view of the top of the stove, showing the lateral extensions thereof. Fig. 4 is a similar view, in which modifications of the valves for controlling the admission of heat to the extensions are represented.

Similar letters of reference in the several figures denote the same parts.

My invention consists in certain novelties of construction and combinations of parts, which I will first describe, and then point out particularly in the claims.

In the drawings, A represents the base of the stove, having an oil-chamber, B, and supporting-legs C.

D is the drum or body of the stove, having lateral arms d, by which it is supported in bearings e in upwardly-projecting lugs E—preferably three in number—on the base, as shown in Figs. 1 and 2. The drum is divided into three compartments or flues, D' D² D³, by means of partitions f f, and it has a bottom plate, D⁴, through openings in which the lamp-wicks are adapted to pass.

Formed upon or bolted or otherwise firmly secured to the upper end of the drum is the top of the stove, G. This top has three openings, G' G² G³, in its bottom, leading respectively from the flues D' D² D³, and it also has lateral extensions, preferably four in number, H' H² H³ H⁴. The extensions each have a lateral discharge opening, h, for the heat, and some or all of them are provided with a suitable valve, which, when turned in position, is adapted to close the heat-discharge openings, and when turned in another position is adapted to prevent the heat from entering said extensions from the heat-flues of the drum. In Fig. 3 two of the extensions, H' H³, are represented

as being larger than the other two extensions, H² H⁴. The valves in the smaller extensions are indicated by the letters I. I. They may be turned so as to wholly or partially exclude the hot air from the extensions or to permit of more or less of it escaping therefrom. In Fig. 4 different arrangements of valves are represented in the various extensions. The construction of the top is such that a large vessel may be heated over the middle portion of it, and at the same time various smaller vessels may be subjected to greater or less heat in the several extensions. The heat arising through the drum strikes the bottom of the large central vessel and is deflected into the extensions, thereby being doubly utilized. When a central vessel is not in position a plate or web, J, is placed over the center of the top, as shown in Figs. 3 and 4, and said plate then serves to deflect the heat into the extensions, the same as the large vessel does when it is used. The top and its extensions being permanently affixed to the drum or body of the stove, the latter can be tilted on its articulated bearings to permit of access to the lamp, or for any other purpose, without the necessity of lifting off a top, as in the case of the ordinary oil-stoves.

K represents a metal plate forming the top of the oil-chamber B. This plate has a central tube, k, and angular corner-pieces k', as shown in Fig. 2. Resting upon the tube k and held in place by the corner-pieces k' is another plate, L, to which the wick-tubes l l l are attached, as shown in Figs. 1 and 2. The wick-tubes extend up into the converging openings in the bottom plate, D⁴, of the drum; but their lower ends terminate at or slightly below the plate L, thus leaving an open space between them and the top plate of the oil-reservoir. Direct metallic communication between the wick-tubes and the oil-reservoir is thus prevented, and the danger of generation of gases and explosion in the latter is obviated.

A perforated plate, N, may be fitted over the wick-tubes, if desired, as shown in Figs. 1 and 2.

Prior to my invention all oil-stoves which have been adapted to the heating of several separate vessels at the same time have been provided with a removable top, which was capable of being placed upon and taken off of the drum or body of the stove, and which was a separate and independent structure in itself.

When the top was lifted the body of the stove was not disturbed, and when the body of the stove was tipped in taking it off its base with the top upon it the latter was liable to fall off 5 and become broken. The ordinary method of attaching the body of the stove to the base consisted in forming vertical standards or posts on the base, and in providing in the bottom plate of the body a series of holes or perforations for the reception of the said standards or posts of the base. When it was desired, for any purpose, to get at the heating-lamps, it was necessary to lift the whole body of the stove until it was clear of the base, and then 10 set it to one side while inspecting or arranging the lamps. So, too, in prior oil-stoves no means of controlling the admission of heat into the several lateral extensions of the top or of cutting the heat off therefrom was employed, 15 and the consequence was that when the opening in any one of the lateral extensions was left uncovered by the removal of a vessel or covering-plate therefrom the heat all tended toward that opening as the easiest avenue of 20 escape, and the other extensions were not properly or sufficiently heated.

My invention, it will be observed, obviates all the above-named objections to the old form of oil-stoves. In the first place, the top and 30 body of the stove are so connected together as to form practically a single structure, or, in other words, the body merges into the top and the lateral extensions of the latter form simply continuations of the flue or flues in the body. When the top is moved the body is also moved, and the former cannot fall off when the body is tipped. So, therefore, when it is desired to inspect the lamps, it is not necessary to take off first the top and then the body, 35 but both are removed out of the way as a unity. In the second place, the body of the stove is articulated to the base, so that when it is desired to have access to the lamps it is only necessary to tip the body of the stove in its articulated bearings to effect the object, 40 without the labor of lifting the body entirely from the base, and then after fixing the lamps placing the body back upon the base with the openings in its lower plate properly registered 45 with standards or posts on the base, as heretofore, and this turning or tilting of the body does not permit of the top falling off, as the latter is formed integral with it, as aforesaid. In the third place, by the valves which I employ in the upper part of the stove I am 50 enabled to admit the heat into any or all of the lateral extensions in any desired quantity, or to entirely exclude it therefrom at pleasure, and by such an arrangement all the extensions 55 of the top may be utilized for cooking different articles at the same time under different degrees of heat, and when a vessel is removed from one of the extensions the valve in that extension can be closed, so as to prevent the 60 flowing out of the heat through that extension and the diminishing of the heat in the other extensions. The lateral opening of each

of the extensions affords the necessary exit for the heated air when the valves are partially or wholly opened. The valves are so arranged that while they are capable of controlling the quantity of heat admitted into the extensions, they are also adapted by co-operation with the discharge-openings to regulate the amount of heated air discharged from the 75 extensions. These improvements in construction in my stove, it will be seen, make it a greatly superior structure to the oil-stoves that have preceded it.

There are several features of my herein-described oil-stove which I have not claimed herein, as they form the subject-matter of a separate application—a division of the present case, designated as "Division B."

I claim as my invention—

1. An oil-stove having a heat-conducting drum, a rigidly-attached top having lateral extensions or vessel-supports, and valves for controlling the admission of heat into the extensions, substantially as described.

2. An oil-stove having a heat-conducting drum, a rigidly-attached top having lateral extensions or vessel-supports, a central heat-deflecting plate or web, and valves for controlling the admission of heat into the extensions, substantially as described.

3. The combination, with the oil-reservoir, of the plate K, having the central tubular support and the angular corner-pieces, and the plate L, carrying the wick-tube, the whole arranged and operating substantially as described.

4. An oil stove provided with a top having lateral extensions, each adapted to hold a separate vessel, and having valves for controlling the admission of heat into the several extensions, substantially as described.

5. In an oil-stove, the combination of the following elements, viz: a body or drum having one or more heat-conducting flues, a top having openings corresponding to the number of flues, and having lateral extensions with open tops for holding and receiving separate vessels, some of said extensions having the heat-flues of the drum opening directly into them, and others of said extensions being removed from said flues and receiving only such heat as is laterally deflected into them after emerging from the flues of the drum, and having rests for supporting a central vessel or deflecting-plate, as described, a base-plate for the body or drum, means for rigidly connecting the extension-top to the base-plate, so as to hold the structure solidly and permanently together, and a base containing a lamp or lamps, upon which the stove-body rests, as set forth.

6. In an oil or gas stove, a top having a lateral extension provided with a valve capable of closing either the entrance to or the exit from said extensions.

GEO. H. FERRIS.
